UNITED STATES PATENT OFFICE

103,828

DESIGN FOR AN AUTOMOBILE HOOD

Amos E. Northup, Detroit, Mich., assignor to Willys-Overland Motors, Inc., Toledo, Ohio, a corporation of Delaware

Application January 14, 1937, Serial No. 67,058

Term of patent 14 years

To all whom it may concern:

Be it known that I, Amos E. Northup, a citizen of the United States, residing in the city of Detroit, county of Wayne, and State of Michigan, have invented a new, original, and ornamental Design for an Automobile Hood, of which the following is a specification, reference being had to the accompanying drawing, forming part thereof,

In the drawing, Figure 1 is a perspective view of an automobile hood showing my new design;

Figure 2 is a top plan view of the hood illustrated in Figure 1.

I claim:

The ornamental design for an automobile hood substantially as shown.

AMOS E. NORTHUP,
